UNITED STATES PATENT OFFICE

156,257

DESIGN FOR A HIGH-VOLTAGE CAPACITOR

Arnold G. Kling and Bert H. Marks, Milwaukee, Wis., assignors to Globe-Union Inc., Milwaukee, Wis., a corporation of Delaware

Application June 23, 1948, Serial No. 147,144

Term of patent 14 years

(Cl. D26—1)

To all whom it may concern:

Be it known that we, Arnold G. Kling and Bert H. Marks, citizens of the United States, residing at Milwaukee, in the county of Milwaukee and State of Wisconsin, have invented a new, original, and ornamental Design for a High-Voltage Capacitor, of which the following is a specification, reference being had to the accompanying drawing, forming a part thereof, and in which:

Fig. 1 is a view in front elevation of a high-voltage capacitor, showing our new design, a fragmentary part being shown in section for the sake of clarity in illustration; and

Fig. 2 is an end elevation thereof, each end being identical.

We claim:

The ornamental design for a high-voltage capacitor, as shown and described.

ARNOLD G. KLING.
BERT H. MARKS.
